UNITED STATES PATENT OFFICE.

EDWARD N. DICKERSON, OF NEW YORK, N. Y.

ACETYLENE-GENERATOR.

SPECIFICATION forming part of Letters Patent No. 603,678, dated May 10, 1898.

Application filed August 12, 1897. Serial No. 647,958. (No model.)

To all whom it may concern:

Be it known that I, EDWARD N. DICKERSON, of No. 253 Broadway, in the city of New York, county and State of New York, have invented 5 a new and useful Improvement in Acetylene-Generators Especially Applicable to Portable Lamps, of which the following is a full, true, and exact description, reference being had to the accompanying drawings.

10 My invention relates to that class of lamps in which a water-chamber is located above a calcium-carbid holder and the water is allowed to pass slowly, generally drop by drop, into the calcium-carbid chamber.

15 My invention relates especially to a new and improved form of cartridge in which the calcium carbid is held and which can be ejected at the end of the generation and a new one replaced.

20 My invention will be readily understood from the accompanying drawings, in which—

Figure 1 represents an elevation, partly broken away, of my lamp; Fig. 2, a cross-section through the generating portions of the 25 lamp; Fig. 3, a cross-section through Fig. 2 on the line $x-x$; Fig. 4, a vertical section through the carbid cartridge, Fig. 2, showing a slight modification; and Fig. 5, a similar view to that of the carbid cartridge, Fig. 2, 30 showing the water-distributing tube in position.

1 represents the body of my lamp; 2, the water-receptacle; 3, the burner, which, as shown, is connected with the generating chamber by the condensing-tube 4, located in 35 the water-chamber. These structures may be of any desired form, and the condensing-tube may be omitted, if desired. The water is supplied to the water-chamber through the cap 5.

6 represents my improved cartridge, which is of flexible material, preferably of the general arrangement used in tubes for holding paint and similar matters. These cartridges 45 are made of thin metal and are provided with screw-caps. I propose to use a similar cartridge of suitable size for the requisite amount of carbid. I also propose to close the upper part of these tubes permanently by a film or 50 septum 7. This may be arranged, as in Fig. 5, at the end of the screw-thread, or may be part of the lower metallic body, as shown in

Fig. 4. In Fig. 4 an additional screw-cap 8 is shown; but this is not necessary. This cartridge is filled in the usual way and is then 55 closed at the bottom, as at 9. It is preferably provided with folds 10, allowing of the expansion, so as to accommodate itself to the increased volume of the carbid when the same is converted into lime. The same result can 60 be accomplished less advantageously by only partially filling the tube with calcium carbid and allowing it to expand upward as it is converted.

The lower part of the water-receptacle 2 is 65 provided with a suitable valve-support 11, closed by a needle-valve 12, which may be operated by a handle 13, extending to the outside of the lamp-casing. As shown, this handle 13 is arranged with a spring and jaw 70 to clamp onto the flattened end of the valve-stem 12.

The drip-tube 14 is fed from the valve 12, water passing down through the opening 15 at the bottom of the water-chamber. The 75 upper part of this metallic portion may also be connected with the condensing pipe-conveying tube 4. A suitable screw-socket 16 surrounds the tube 11 and is supported thereon by the reentering lip or collar 17, resting 80 upon the collar on the tube 11. The lower end of this revolving piece is screw-threaded, as at 18, to fit the screw-thread on the upper end of the cartridge. Any suitable packing 85 may be employed to make a tight joint between the cartridge-tube and the lamp.

In operation the film or septum 7 is broken, as shown in Fig. 2, by a suitable punch. Then the tube-cartridge is screwed in position by revolving the screw-collar 14, and on 90 opening the valve 12, allowing the drip, the operation commences at once. In case a considerable quantity of carbid is to be treated I prefer to use a distributing-tube 19, as shown in Fig. 6. This is by preference made of 95 punched waxed paper and is held in position in the collar or neck of the tube-cartridge 6. As shown, it is arranged at an angle, so that the water will strike upon its sides and feed out through the small openings. This 100 tube does not have to be made tight, and consequently a stiff piece of paper can be bent into tubular form and swung into position, as shown in Fig. 5. Then the carbid being

filled around it and the lower opening sealed the cartridge is permanent. As the carbid is converted into lime the tube itself will somewhat collapse, and where the external flexus 5 or bend is employed, as in Fig. 3, the cartridge will also open to correspond to the increased volume of the lime.

What I claim as my invention, and desire to secure by Letters Patent, is—

10. 1. The calcium-carbid cartridge, consisting of a laterally-extensible air-tight vessel provided with a pierceable air-tight film covering its opening, substantially as described.
15. 2. The combination in an acetylene-gas generator, of a pierceable air-tight cartridge, having a screw-neck provided with a pierceable film, a water-chamber connected therewith, and a screw connection between the water-chamber and said neck for making a gas connection, substantially as described.

3. The combination in an acetylene-gas generator of the water-chamber, the laterally-expansible carbid-receptacle, and means for detachably connecting the same, substantially as described.

4. The combination in a carbid cartridge, of a pierced water-tube located at an angle within said cartridge, substantially as described.

5. The combination of the laterally-expansible metallic cartridge 6, having screw connection 7, and pierced paper tube 19, substantially as described.

In testimony whereof I have signed my name to this specification in the presence of 3 two subscribing witnesses.

E. N. DICKERSON.
